UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

PLATE-CLAMPING DEVICE FOR ROTARY CYLINDER PRINTING-PRESSES.

1,052,206.

Specification of Letters Patent.

Patented Feb. 4, 1913.

Original application filed March 15, 1909, Serial No. 483,600. Divided and this application filed June 7, 1909. Serial No. 500,596.

To all whom it may concern:

Be it known that I, HENRY F. BECHMAN, of Battle Creek, in the county of Calhoun and State of Michigan, have invented certain new and useful Improvements in Plate-Clamping Devices for Rotary Cylinder Printing-PresSES; and I hereby declare that the following is a full, clear, and exact description thereof, reference being had to the accompanying drawings, which form part of this specification.

This invention relates to rotary-cylinder web-printing presses wherein the printing surfaces are formed on stereotype plates fastened upon the peripheries of the plate cylinders and co-acting with adjacent impression cylinders to print a web.

The primary object of the present invention is to provide means for quickly and easily fastening tubular plates on the cylinders of the press described in my Patent Number 867,230, dated October 1, 1907; and Number 979,919 dated December 27, 1910 of which latter the present case is a division. In said press the plate cylinders are of small diameter, and are designed for use with tubular stereotype plates adapted to be slipped endwise on and off the plate cylinders.

The present invention consists in the novel means for securing stereotype plates on the cylinders as hereinafter described and claimed; and in the accompanying drawings I have shown the invention as applied to a plate cylinder adapted to carry two tubular single page plates arranged end to end thereon; but the novel clamps can be applied to cylinders carrying three or more tubular page-plates; and to ordinary plate cylinders.

I will now describe the invention in detail, as illustrated in the accompanying drawings, and in the claims summarize the parts and combinations of parts for which protection is desired.

In said drawings—Figure 1 is an enlarged sectional elevation of a plate cylinder of a rotary press equipped with my plate-fastenings clamping a plate. Fig. 2 is a similar view of such plate cylinder showing the plate-fastenings in disengaged position. Fig. 3 is an enlarged top plan view of the end plate securing devices. Fig. 4 is a section on line 4—5, Fig. 3, showing the end clamp in position to enter the

slot and clamp a plate. Fig. 5 is a similar section on line 4—5, Fig. 3, showing the clamp in position to permit the removal of a plate. Fig. 6 is an enlarged detail section on line 6—6, Fig. 1.

A striking feature of the press shown in my aforesaid patent and application is the diminutive size of the plate cylinders; in practice the circumference of each plate cylinder when the plate is on is merely equal to the length of one ordinary newspaper page—plus the desired margins between successive impressions,—whereas in ordinary presses the circumference of the cylinders is at least twice as great. With such small cylinders I use tubular stereotype plates each of which practically surrounds the circumference of the cylinder. Each plate is bored to fit closely and neatly around the periphery of the cylinder but has a longitudinal slot to engage the edges of a rib 1^c on the cylinder, which rib keeps the plates in proper alinement on the cylinder,—and also forms an abutment by which the plates are caused to turn therewith. Such plates can be placed on or removed from the cylinders only by slipping them endwise on or off the cylinders. The only fastening devices required for these plates therefore are means for preventing lateral movement of the plates on the cylinders during the operation of the press which means forms the subject of the present case.

In order to facilitate securing the plates on the plate cylinders or removing them therefrom I have provided the plate cylinders with novel plate securing devices which are adapted to disappear when disengaged from the plates, and to come into locking position when the plates are placed on the cylinder. I will now describe these devices.

The plate cylinders are shown as but two pages wide, so that both plates can be conveniently slipped on or off the same end of the cylinder. Each plate cylinder 1^a is provided with one or more slots 1^d in which is placed an ordinary plate clamp or slide block 2 which is provided with lateral flanges 2^a engaging grooves in the sides of the slot 1^d, as usual. The inner end 1^b of this slot is deepened and inclined and the side grooves are similarly inclined inwardly toward the axis of the cylinder so that when the clamp 2 is moved longitudinally of the slot

and toward the inner end of the slot it gradually disappears below the surface of the cylinder (see Fig. 2); but when the clamp 2 is moved toward the outer end of the slot 1^a it will rise in the slot and project above the surface of the cylinder (see Figs. 1 and 6). To the clamp block 2 is attached a rod 2^b which extends in a channel 1^f leading from the slot 1^a toward the end of the cylinder, and said rod 2^b is provided on its extremity with a finger 2^c which projects sufficiently above the surface of the cylinder to engage the edge of a plate P slid on the cylinder. Before the first plate P is placed on the cylinder the clamp 2 is moved back into the lower portion of the slot 1^a and disappears below the surface of the cylinder as described (see Fig. 2); then the plate is slipped onto the cylinder, and as it is slid inwardly thereon its forward edge engages the finger 2^c and moves rod 2^b thereby causing clamp 2 to rise beside and against the inner edge of the plate (see Fig. 1). Then when the second plate P is slid on the cylinder it catches the said clamp 2 and causes it to move the first plate P on until it abuts against a stop 1^w on the cylinder which arrests the plates in correct printing position. The second plate P is then clamped against linear movement on the cylinder, by means of a slide block or clamp 3 (Figs. 1-5) which is strung on a threaded bolt 4 by which the clamp can be moved longitudinally of the slot. Said bolt 4 extends through the head 1^r of the cylinder and into a slot 1^k in the cylinder, said slot being dove-tailed or undercut at 1^m for engagement with flanges 3^a on the sides of the clamp 3. Bolt 4 has a collar 4^b on it bearing against the inner side of head 1^r to prevent longitudinal displacement of the bolt. At the outer end of the slot 1^k is an enlarged recess 1°, and when clamp 3 is backed out into this recess (by reversely rotating bolt 4) it can be turned over into the position indicated in Figs. 2 and 5, so that it disappears below the surface of the cylinder; in which position the plates P can be easily slid on or off the cylinder.

When the clamp 3 is entered in slot 1^k it cannot turn on bolt 4, and consequently can be moved backward or forward in the slot, by properly rotating bolt 4. While in engagement with the slot the clamp projects above the surface of the cylinder into plate engaging position (see Figs. 1 and 4). If the clamp 3 be backed out of slot 1^k into recess 1°, it will turn with the bolt and may then be turned over into the position indicated in Fig. 5, and disappear below the surface of the cylinder, so that plates P can be readily slipped on or off the cylinder. In order to facilitate turning clamp 3 into either operative position (Fig. 4), or inoperative position (Fig. 5), it is formed with

projecting lugs 3^d, 3^e, on opposite sides, and preferably at the outer ends of its side flanges, and adapted to engage a pin or stud 5 attached to the head 1^r of the cylinder and projecting into the recess 1° as shown. The parts are so proportioned that just after clamp 3 is backed out of slot 1^k into recess 1°, and the clamp starts to rotate with bolt 4, lug 3^d will strike pin 5 and arrest the rotation of clamp 3, when the clamp is in the position indicated in Fig. 5, in which the clamp has disappeared beneath the surface of the cylinder. Then when it is desired to reenter clamp 3 into slot 1^k bolt 4 is turned in the opposite direction, and clamp 3 turns therewith until lug 3^e strikes pin 5, and arrests the rotation of clamp 3 when it is in exact position to reenter slot 1^k. In this way the clamp 3 is readily shifted into engaging or disengaging position, and the operator is not annoyed or delayed in positioning the clamp. After both plates have been slid on the cylinder as described, the bolt 4 is turned so as to first bring clamp 3 into the position indicated in Fig. 4 so that its flanges 3^a can enter the grooves 1^m in the sides of slot 1^k, and so that it projects above the surface of the cylinder, in position to engage a plate; then bolt 4 is rotated so as to move clamp 3 inward against the edge of the second plate P and cause the latter to engage clamp 2 and cause it to hold the first plate P in position, (see Fig. 1). Thus it is practically only necessary in securing the plates on the cylinder to operate bolt 4, as the intermediate clamp 2 will be automatically positioned by the act of slipping the first plate on or off the cylinder.

I have illustrated but one set of plate-fastening devices on the cylinder, but obviously more sets could be used on each cylinder according to the size and number of plates to be secured thereon.

Having described my invention what I claim as new and desire to secure by Letters Patent thereon is:

1. In combination, a plate cylinder having a slot, and a plate clamp slidably mounted in said slot and adapted to engage the edge of a plate, means for moving said clamp longitudinally of the slot, said clamp being adapted to disappear beneath the surface of the cylinder when moved to one end of the slot, and to project above the surface of the cylinder when moved to the other end of the slot.

2. In combination, a plate cylinder having a slot, and a plate clamp adapted to engage the edge of a plate slidably mounted in said slot, said slot being deepened at one end so that when the clamp is retracted it will disappear beneath the surface of the cylinder, substantially as described.

3. In combination, a plate cylinder having a slot, and a plate clamp adapted to engage

the edge of a plate slidably mounted in said slot, and means for shifting the clamp in the slot, said slot being enlarged at one end so that when the clamp is moved to that end 5 of the slot it will disappear.

4. In combination, a plate cylinder having a slot, a plate clamp slidably mounted in said slot, said slot being deepened at one end so that when the clamp is retracted it 10 will disappear, and means connected with said clamp and adapted to be engaged by a plate to move the clamp into operative position.

5. A plate cylinder having a longitudinal slot, a plate clamp movably secured in said slot and adapted to disappear beneath the surface of the cylinder when moved to one end of the slot, and a rod connected with said clamp and adapted to be engaged by the 20 edge of a plate and move the clamp into operative position as the plate is positioned on the cylinder.

6. A plate cylinder adapted to carry tubular plates having a longitudinal slot deepened at one end, a plate clamp movably secured in said slot and adapted to disappear beneath the surface of the cylinder when moved to the deeper end of the slot, a rod connected with said clamp and having a 30 finger on its free end adapted to be engaged by the edge of a plate and thereby caused to move the clamp into operative position as the plate is slid forward on the cylinder.

7. In combination, a plate cylinder having a slot, a bolt extending longitudinally through said slot, a longitudinally movable plate clamp on said bolt adapted to project above the surface of the cylinder and move toward the plate when in plate engaging 40 position, and to turn with the bolt and disappear beneath the surface of the cylinder after it has been moved away from the plate.

8. In combination, a plate cylinder having a slot, an enlarged recess at the end of said 45 slot, a bolt extending longitudinally through said recess and slot, a movable clamp on said bolt adapted when entered in the slot to project above the surface of the cylinder in plate-engaging position, and to turn on the

bolt and disappear beneath the surface of 50 the cylinder when it is moved out of the slot and into the recess.

9. In combination, a plate cylinder having a slot, a bolt extending longitudinally through said slot, a plate clamp on said bolt 55 adapted to project above the surface of the cylinder when engaged with the slot, and to turn on the bolt and disappear beneath the surface of the cylinder when disengaged from the slot, and means for arresting the 60 rotation of the clamp when it has been turned to disappearing position, or returned to position for reentry into the slot.

10. In combination, a plate cylinder having a slot, a recess at the end of the slot, a 65 bolt extending longitudinally through said slot and recess, a plate clamp on said bolt adapted when in the slot to project above the surface of the cylinder in plate-engaging position, and to turn on the bolt and disappear beneath the surface of the cylinder when it is moved out into the recess, and means to arrest the rotation of said clamp when in the recess so as to stop the clamp 70 in disappearing position, or in position to reenter the slot.

11. In combination, a plate cylinder having a clamp-receiving slot, a recess at the end of said slot, a rotatable bolt lying in said recess and slot, and a pin projecting 80 into said recess; with a plate clamp strung on said bolt and adapted to project above the surface of the cylinder in plate engaging position when in the slot; and to turn with the bolt and disappear below the surface of 85 the cylinder when moved into the recess, said clamp having lugs adapted to engage said pin, to prevent rotation of the clamp on the bolt after the clamp is in disappearing position, or has been turned back to slot-engag- 90 ing position, substantially as set forth.

In testimony that I claim the foregoing as my own, I affix my signature in presence of two witnesses.
